UNITED STATES PATENT OFFICE

162,124

ELECTRIC LIGHTING FIXTURE

John W. Brooks, Syracuse, N. Y., assignor to
Pass & Seymour, Inc., Syracuse, N. Y., a corporation of New York

Application July 26, 1950, Serial No. 11,416

Term of patent 14 years

(Cl. D48—23)

To all whom it may concern:

Be it known that I, John W. Brooks, a citizen of the United States, residing at Syracuse, in the county of Onondaga and State of New York, have invented a new, original, and ornamental Design for an Electric Lighting Fixture, of which the following is a specification, reference being had to the accompanying drawing, forming a part hereof, and in which

Fig. 1 is a side elevation of an electric lighting fixture showing my new design; and

Fig. 2 is an end elevation thereof.

I claim:

The ornamental design for an electric lighting fixture, substantially as shown.

JOHN W. BROOKS.
